(57) **CLAIM**

The ornamental design for a radiator for a water cooler, as shown and described.

DESCRIPTION

FIG. 1 is a perspective view of a radiator for a water cooler according to the present invention.

FIG. 2 is a front view of the radiator according to the present invention.

FIG. 3 is a rear view of the radiator according to the present invention.

FIG. 4 is a left side view of the radiator according to the present invention; the right side view of the radiator is a mirror image of FIG. 4.

FIG. 5 is a top plan view of the radiator according to the present invention.

FIG. 6 is a bottom plan view of the radiator according to the present invention; and,

FIG. 7 is a perspective view illustrating of the radiator according to the present invention.

The broken lines showing of the environment are for illustrative purposes only and form no part of the claimed design.
